Primary Examiner — Cynthia R Underwood

(74) Attorney, Agent, or Firm — Diederiks & Whitelaw, PLC; Annette M. Frawley, Esq.

(57) **CLAIM**

I claim the ornamental design for a food container, as shown.

DESCRIPTION

FIG. 1 is a perspective view of a food container, according to the present invention;

FIG. 2 is a left side view of the food container of FIG. 1, with the right side view being a mirror image thereof;

FIG. 3 is a top end view of the food container of FIG. 1; FIG. 4 is a bottom end view of the food container of FIG. 1; and,

FIG. 5 is a cross-sectional view of the food container taken along line 5-5 in FIG. 2.

1 Claim, 5 Drawing Sheets(56)
